JOSEPH EDWARD FAZAKERLEY, OF PITTSFIELD, MASSACHUSETTS.

MECHANICAL LADLE-SKIMMER AND HEAT-PROTECTOR.

1,139,960.

Specification of Letters Patent.

Patented May 18, 1915.

Application filed May 4, 1914. Serial No. 836,248.

To all whom it may concern:

Be it known that I, JOSEPH EDWARD FAZAKERLEY, a citizen of the United States, residing at 913 Tyler street, Pittsfield, Massachusetts, in the county of Berkshire, Massachusetts, have invented a new and useful Mechanical Ladle-Skimmer and Heat-Protector, of which the following is a specification.

10 This invention relates to molders' pots or ladles and more particularly to improved skimming attachments therefor.

An object of the invention is to provide an improved skimming device, applicable to the 15 usual molder's ladle, whereby the molder may skim, hold back and prevent from flowing into the mold, all dross and flux.

Another object is to provide a device of 20 the class described in which the skimming blade is normally held away from the mouth of the ladle but may be conveniently depressed into skimming position by the molder's hand.

Another object is to provide in connection 25 with such a device, a deflector to protect the molder's hand from heat when operating the skimmer.

Other objects and advantages will appear 30 in the detailed description to follow.

In the molding art it is well-known that 35 molten metal contains many impurities which rise to and float upon the surface of the molten metal. This floating mass of impurities is commonly called "dross." In casting metal from the ladle into the mold it is necessary either to skim and remove the dross from the ladle entirely or to hold it back in some manner to prevent its entrance into the mold. Commonly, an assistant 40 takes a bar or other implement and holds back the dross while the molder pours. While this method is effective and satisfactory it requires additional labor. I seek to provide an attachment to a molder's ladle, 45 whereby the molder may do his own skimming with the expenditure of little additional effort. Thus, a considerable saving in labor is obtained.

In general, my device comprises a skimming blade pivoted to a clamp member, together with mechanism to operate the blade, which mechanism is also attached to the clamp member. The latter is readily attached to the handle of the ordinary molder's ladle and can be applied in a few minutes.

As all the parts of my device are attached to this clamp member, the apparatus is unitary in structure and requires but one operation for its attachment. The skimming blade is suitably connected by links to an operating lever which is adapted to be operated by the hand of the molder. A heat deflecting shield is mounted adjacently to the skimming blade to protect the molder's hands from the excessive heat of the molten metal. The skimming blade is normally held away from the mouth of the ladle but can instantly be operated by the molder with one hand, when desired. When the blade is in depressed position it lies inside the ladle and closely adjacent the lip thereof, so that it holds back the dross, flux and cinder and prevents the entrance of the same into the mold.

A preferred form of my invention is illustrated in the accompanying drawings in which:

Figure 1 is a plan view of my device applied to a molder's hand-ladle; Fig. 2 is an elevational view thereof, and Fig. 3 is a detail view of the skimming blade.

Referring to the drawings, 1 represents the usual molder's ladle which is provided with the usual outlet lip 4. 2 is the usual ladle ring which receives and supports the conical pot 1, as clearly shown in Fig. 2. The ring 2 is provided with a long handle 3 which is formed integral therewith. 18 is a semi-cylindrical member, hereinafter called the clamp member which is adapted to fit over the handle 3. The clamp member 18 is, furthermore, provided with pairs of depending lugs 18' on each side thereof which extend below the handle 3. Screws 19 pass through each pair of lugs 18' and securely clamp the member 18 to the handle 3.

The clamp 18 forms a frame upon which all the parts of my device are mounted. Pivoted to the member 18 at 10 is a lever 6. The portion of the lever 6, extending above the pivot 10, is adapted to receive the skimming blade and the heat deflector. The portion of the lever 6, which extends below the pivot 10, is connected at 11 to a link 12. The latter is pivotally connected at 13 to an upwardly extending member 15 which is formed integral with a handle 16. The handle 16 is substantially semi-circular in cross section and is formed to fit the hand. The handle 16 together with the integral extension 110

15 is pivoted to the clamp member 18 at 14. A coiled spring 17, suitably mounted and interposed between the clamp member 18 and handle 16, restrains the link and levers 5 in the position shown in Fig. 1.

Secured to the upper portion of the lever 6 is the skimming blade 5. The latter, as clearly shown in the drawings, is spoon shaped. A flat integral extension portion 5' 10 (see Fig. 3) is provided with a slot 20. A circular flat member 8, hereinafter called the heat deflector, is provided with a pair of lugs 9, integral therewith and outwardly bent therefrom. The portion 5' of the blade 15 and the upper portion of lever 6 are adapted to lie within the pair of lugs 9, as clearly shown in Fig. 1. A thumb screw 7 passes through the lugs 9, lever 6 and the portion 5' and firmly holds these parts together. The screw 7 is adapted to rest in one of the recesses 21 and by loosening the screw 7, the blade 5 may be moved relatively to the screw 20 by reason of the slot 20. Thus, the blade 5 may be secured in various positions of adjustment. 25

Fig. 2 shows the normal position of the parts of my device and it is to be noted that the skimming blade 5 is removed from the ladle 1.

In practice the ladle is carried by the molder with both hands. The upper portion of the handle is grasped by one hand and the other hand lies on the handle 3 closely adjacent the handle 16. Consequently, when 30 the molder desires to pour the contents of the ladle 1 into a mold, he simply shifts his grip on the lower part of the handle 3 to cover the handle 16. When the latter is depressed the blade 5 is forced downwardly 35 by the levers and link described, until it lies within the ladle 1 and beneath the surface of the molten metal therein. The blade 5 lies closely adjacent the lip 4 of the ladle as shown in Fig. 1. Consequently, when the 40 molten metal is poured from the ladle the spoon shaped blade 5 withholds all flux, dirt and dross from passing with the metal into the mold. As soon as the pouring operation is completed, and the molder's hand is 45 released from the handle 16, the blade is returned to the normal position shown in Fig. 2 by the spring 17. The portion of the blade 5 which lies in the molten metal becomes burned after extended use and the adjustable securing means shown in Fig. 3 50 permits the blade to be moved outwardly. Thus, a fresh unburnt portion may be presented to check the flow of the dross. After the blade 5 has been completely used up, the screw 7 is loosened, the old blade extracted, a new blade inserted and the screw 7 is tightened. The operation of changing blades requires but a few minutes. 55

It is recognized that many changes may 60 be made in the structure herein disclosed

without departing from the scope of my invention which is defined in the appended claims.

What I claim is:

1. The combination with a molder's ladle 70 and handle therefor, a member removably attached to said handle, a blade pivotally attached to said member and adapted normally to be held away from said ladle, means on said handle to move said blade to a position within said ladle and partially below the surface of the molten metal therein, whereby when the metal is poured from said ladle, all dirt and dross is held back and prevented from flowing into the mold. 75

2. The combination with a molder's ladle and a handle therefor, of a frame removably attached to said handle, a lever pivoted to said frame, a spoon shaped blade attached to said lever, said blade adapted normally 80 to be held away from said ladle, and means to force said blade within said ladle adjacent the mouth thereof and partially below the surface of the molten metal therein, whereby when the metal is poured from said ladle, 85 said blade skims and holds back the dross and prevents the same from flowing from the ladle with the metal. 90

3. The combination with a molder's ladle and a handle therefor, said ladle being 95 formed with a lip thereon, of a frame adapted to be clamped to said handle, a lever pivoted on said frame, an operating handle pivoted on said frame, a link connecting said handle and said lever, a spoon shaped blade 100 on said lever, adapted, normally, to be held away from said ladle and adapted, when said handle is operated, to be lowered into said ladle to a position partly below the surface of the molten metal therein, and closely 105 adjacent to the lip of said ladle, whereby said blade withholds the dross on the surface of the molten metal from passing with the metal when the latter is poured from the ladle. 110

4. The combination with a molder's ladle and a handle therefor, said ladle being formed with a lip thereon, of a frame adapted to be clamped to said handle, a lever pivoted thereon, an operating handle pivoted on said frame, a link connection between said lever and said operating handle, a skimming blade removably attached to said lever, a spring interposed between said frame and said operating handle, said spring 115 adapted to hold said blade normally away from said ladle, a deflector also attached to said lever and adapted to protect the molder's hand from heat, when using said operating handle, said operating handle 120 adapted, when depressed, to lower said blade within said ladle to a position partially beneath the upper level of the molten metal therein and closely adjacent the lip of said ladle, whereby said blade withholds all flux, 125

130

dirt, and dross from leaving said ladle with the metal when the latter is poured into a mold.

5. The combination with a molder's ladle and handle therefor, a member removably attached to said handle, a blade pivotally attached to said member and adapted normally to be held away from said ladle, means on said handle to move said blade to a position within said ladle and partly below the surface of the molten metal therein, whereby

when the metal is poured from said ladle, all dirt and dross is held back and prevented from flowing into the mold, and a heat deflector located on said blade and adapted to 15 shield the molder's hands from the heat of the metal within said ladle.

JOSEPH EDWARD FAZAKERLEY.
